[57] CLAIM

The ornamental design for an electronic note pad for
data entry, as shown and described.

DESCRIPTION

FIG. 1 is a perspective view of an electronic note pad
for data entry showing our new design;

FIG. 2 is a front end elevational view thereof;

FIG. 3 is a rear end elevational view thereof;

FIG. 4 is a side elevational view thereof;
FIG. 5 is a side elevational view thereof opposite that
shown in FIG. 4;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
